COMBINATION SWAB AND WASHING TOOL

Filed Nov. 28, 1938

UNITED STATES PATENT OFFICE

2,221,775

COMBINATION SWAB AND WASHING TOOL

Alexander Boynton, San Antonio, Tex.

Application November 28, 1938, Serial No. 242,780

12 Claims. (CL 166—20)

My invention relates to swabs and washing tools for cased wells and is an improvement upon my Patents Nos. 1,510,581, granted October 17, 1924, and 1,520,400, granted December 23, 1924. 5 This invention also relates to means for cleaning old oil and gas wells.

An object is to provide a combination swab and washing tool by substituting only one part for another to quickly and easily convert the tool 10 from a swab to a washing tool, and vice versa.

Another object is to so construct a washing tool that it may be used for a swab without any change, and to so construct a swab that it may be converted into a washing tool by simply drilling 15 holes which may be easily plugged to reconstruct the tool into a swab.

A still further object is to provide a combination swab and washing tool having expandible members protected from abrasion and unnecessary wear by protectors that are easily and cheaply manufactured.

In addition to the foregoing objects, another purpose is to provide a means and method for blowing out deposits from behind liners and out- 25 side of perforated casing by the application of compressed air or gas, which may or may not carry abrasive substances or liquids or in combination with abrasive substances and liquids.

As a swab, the tool causes the expandible member or members to seal off against the well casing or tubing by the force of well fluid above the swab exerted internally of the expandible member or members, a valve being provided proximate the lower extremity of the tool, which valve 35 is adapted to remain open while the swab is being lowered into the well and to close and remain closed by pressure of the fluid raised by the swab while the swab is being withdrawn from the well.

As a washing tool, the device utilizes the pump 40 pressure to expand two expandible members into sealing-off engagement between the tool and the well casing or liner. The pump fluid is then forced out between the expanded members through openings in the well casing or liner, a 45 valve being provided proximate the lower end of the tool, which valve is adapted to normally remain open but which will be closed by the pressure of the wash fluid.

By the term "washing tool" is meant a tool 50 that will cause pump fluid to be discharged through perforations in the casing or through openings in a liner, thereby washing the formation exterior of the casing or liner.

As a clean-out tool the device hereinafter described as a washing tool may be supplied with

compressed air or gas, which may be used pure or in combination with abrasives such as sharp sand, adamantine particles or the like or in combination with a liquid, such as water, oil, naptha, gasoline or any other liquid or combination of liquids or in combination with such abrasives and such liquids adapted to cut, dislodge, and expel from the well, mud, shale, settling, and deposits of all kinds, including paraffin and asphalt. The employment of air or gas, pure or in combination with abrasives, either or both, or in combination with liquids, is primarily intended for use in wells which would be damaged by the application of unaerated liquids or in wells which would allow such liquids to go out into the 15 formation so freely as to render it impossible or impracticable to secure circulation of the pump fluid.

I attain the foregoing objects by mechanism illustrated in the accompanying drawing, in 20 which—

Fig. 1 is a longitudinal section of the swab, the valve and its upper guide member being shown in elevation.

Fig. 2 is a side view of the shield in Figs. 1, 6 25 and 7.

Fig. 3 is a section taken on the line 3—3, Fig. 1.

Fig. 4 is a vertical section illustrating a modified form of part of the body nipple of Fig. 1.

Fig. 5 is a section taken on the line 5—5, Fig. 7. 30

Fig. 6 is a section on the line 6—6, Fig. 1.

Fig. 7 is a longitudinal section of the washing tool, the valve and its upper guide member being shown in elevation.

Similar characters of reference designate similar parts throughout the several views. 35

As a swab, the device as illustrated in Fig. 1 has the upper threaded end of perforated swaged nipple 5 attached to a cable, not shown. The lower end of nipple 5 has threaded connection 40 with coupling 4 which in turn has threaded connection with the swab body mandrel 1 having openings 1c opposite the central portion of expandible members 11. The cups 1a are secured upon mandrel 1 by welds 1b. The expandible 45 members 11, which may be of tough rubber, have a loose fit over mandrel 1. The proximate ends of the expandible members 11 are received within cups 1a and the extreme ends of members 11 are received within the cups 2, the thin metallic 50 shields 18 having channels 18a (see Fig. 2) to receive the ends of wires 12. The shields are in turn received within cups 1a and 2, the latter having threaded connection over the opposite ends of mandrel 1. The cup clamp ring 3 having 55

threaded engagement over the mandrel 1 proximate its upper end, serves to lock the upper cup 2 in close engagement with the upper member 11. The lower cup 2, threadedly engaged over body mandrel 1 is locked in close engagement with lower member 11 by valve seat nipple 6, having threaded engagement over the lower end of mandrel 1. The ends of wires 12, which wires may be of spring steel, are slidably fitted into the channels 18a of shields 18 positioned within the cups 1a and 2, as appears in Figs. 1, 6 and 7.

Between the cups 1a and 2 the expandable members 11 have longitudinal slots to receive the protector wires 12 flush with their outer surfaces, as appears in Fig. 3. These wires are preferably square. In use, their outer surfaces quickly wear to a perfect contour of the pipe, through which the swab is run.

The purpose of shields 18 is to keep the ends 20 of wires 12 free to move independently of the rubbers 11 when the rubbers are expanded to seal off against the pipe in which the swab is operated. In expanding the enlarged central portion of the rubbers expand between cups 1a 25 and 2, while the tapered ends 11a seal tightly against the shields 18 and cups 2. These tapered ends of the rubbers do not stretch as does the central portion. In operation the rubbers maintain a constant end to end length. It is, therefore, apparent that each of the wires 12, in being bent outward by the central portion of rubbers 11 as the rubbers expand, would have to slip between the tapered ends of the rubbers 30 and cups 1a and 2 if the ends of the wires were 35 not separated from the rubbers by the shields 18. The friction between the wires 12 and rubber ends 11a, when the swab acts, would be much greater than the friction between the wires and metal during a similar movement. This is why 40 the shields 18 are provided with channels 18a, Fig. 2, into which channels the wires 12 have a close sliding fit, the depth of channels 18a being approximately the same as the thickness of the wires. It will be noted that the tapered ends 45 11a of rubbers 11 extend lengthwise somewhat beyond the ends of the wires 12 and shields 18. This extension, indicated at 11a', serves at all times while the rubbers are expanded by internal force, to maintain a perfect contact and resulting seal between the rubbers and the metallic cups 1a and 2, respectively. It is apparent 50 that each of the shields 18, or their equivalent, could be manufactured integral with the cups.

The rubbers 11 for both swab and washing 55 tool should be moulded with slots provided in their tapered ends 11a for the channels 18a of shields 18 into which channels the ends of protector wires 12 are closely slidably, as appears in Fig. 6. The ribs between the slots in the tapered 60 ends of the rubber should also be inwardly offset by the wall thickness of the shields 18 in order that the outer surface of the rubber and shields will be in alignment, as is apparent from an examination of Figs. 1 and 6. Manifestly, the slots 65 for the wires in the periphery of the rubbers are in alignment with channels 18a when the tool is assembled. The rubbers and wires, being separate units, whichever wears out first may be replaced at small cost and the maximum service 70 thus obtained from each in both swab and washing tool.

The valve seat nipple 6 has within it a portion of reduced diameter 6a having a valve seat 6b. The spring cage nipple 7 has threaded connection 75 within the lower end of nipple 6. The valve

10, adapted to become engaged upon the seat 6b, is normally held open, as shown in Figs. 1 and 7, by coiled spring 8, preferably installed under some compression, and which has its lower end seated upon fins 7b proximate the lower end of nipple 7 and its upper end engaged under the fins 9a of spring rider 9 which latter member may be pressed over valve stem 10a and secured upon it by welds 10b and 10c. The lower end of the valve stem has a free sliding fit within the 10 guide ring 7a, integral with the fins 7b. The fins 9a, having a free sliding clearance within nipple 7, normally engage under the internal portion of reduced diameter 6a, thereby supporting the valve 10 in its open position, as appears in Figs. 15 1 and 7.

To function as a swab, the device illustrated in Fig. 1 may be attached to a cable at the upper end of nipple 5 and lowered into the well. It will be understood that the swab rubbers 11 and protector wires 12 have a slight but free clearance such as $\frac{1}{8}$ " to $\frac{1}{4}$ " within the pipe being swabbed through, not shown but similar, excepting the perforations, to pipe 17 in Fig. 7. As the swab is lowered, the ample opening between valve 10 25 and its seat 6b and the large openings between fins 9a, through spring 8, through fins 7b and through the perforations 5a of nipple 5 provide ample entrance space for well fluid in order that the swab will descend rapidly through it until 30 the swab has been properly submerged. The cable (not shown) attached to nipple 5 is then raised. All openings, except perforations 5a, may be approximately equal to each other. The perforations 5a should be aggregately larger than 35 either of the other openings in order that pressure will transmit with little resistance from above the swab to valve 10 when the cable is raised.

If the swab, inadvertently, be lowered too deep 40 into the well fluid to be safely withdrawn by the cable, the swab may be again lowered until the pressure becomes nearly equalized above and below the valve; whereupon the expansive force of spring 8 will raise the valve. The swab may 45 then be raised slowly, so as not to seat the valve until the excess load of well liquid above the swab has been allowed to pass through it; whereupon the cable is raised more rapidly to again seat the valve as the swab is withdrawn from 50 the well.

Fig. 4 shows that the swab illustrated in Fig. 1 can be changed into a washing tool to function as will hereinafter be explained for the construction illustrated in Fig. 7 by merely drilling 55 holes 1d through the mandrel 1 between the cups 1a. Fig. 4 further illustrates that the swab converted into a washing tool, as above stated, can be easily and quickly reconverted into a swab by closing the holes 1d with clamps 13 and 60 gaskets 15 by means of bolt 14.

To function as a washing tool Fig. 7 shows the wash pipe threadedly joined to the washing tool body nipple 1A by coupling 4. The nipples 6, 7 and contained valve 10, spring 8, and spring rider 65 9 are connected upon the lower end of body mandrel 1A in the same manner as they are shown connected to the mandrel 1 in Fig. 1, and serve related purposes to those stated in connection with the construction shown in Fig. 1. The opposite ends of expandable members 11 and protector wires 12 are received in cups 1Aa and 2, respectively, similar to their reception in Fig. 1, the cups 1Aa preferably being cast integral with the body mandrel 1A. The rubbers 11 prefer- 70 75

ably have a slight clearance such as $\frac{1}{2}$ " over the body nipple. The shields 18 are the same in construction and purpose as stated in connection with Fig. 1.

5 In operation the washing tool is lowered into the well upon wash pipe 16 which, it is understood, may be connected to a pump at its upper end. While the tool is being lowered into the casing, well fluid may enter the wash pipe 16 between fins 17b, through spring 8, between fins 9a, and pass by valve 10 as is apparent. The washing tool expandable members 11 and wires 12 have a free but slight clearance such as $\frac{1}{16}$ " to $\frac{1}{8}$ " within the casing or liner 17 to be washed through. When the tool has been lowered to where perforations in the pipe to be washed through are positioned between the expandable members 11, as appears in Fig. 7, the pump is started. The pump pressure then closes valve 10 upon its seat 6b and expands rubbers 11 by pressure exerted interior of them through openings 1Ac. The pump wash fluid then goes out through slots 1Ab, through the perforations 17a in the casing or liner 17 and up outside the casing or liner into the perforations 17b above the upper rubber, through which perforations the wash water enters the pipe being washed through, whence the wash water continues upward and out of the well via the annular opening 17c between the wash pipe 16 and the casing or liner 17.

In order to secure circulation for the wash water it will be noted that the upper rubber 11 must be positioned below at least one perforation in the pipe being washed through, as is apparent in Fig. 7.

In order to cause the maximum pump pressure to contact the formation through perforations 17a it is necessary that the total discharge area 40 of slots 1Ab should be relatively much greater than the aggregate discharge area of perforations 17a between the rubbers 11.

The protector wires 12 provide that the washing tool may be moved in the casing or liner 45 while the rubbers are expanded without greatly damaging the rubbers as they pass over the perforations.

A comparison of Figs. 1 and 7 shows that the swab illustrated in Fig. 1 can be converted into 50 a washing tool, as shown in Fig. 7, by merely substituting the washing tool body mandrel 1A in place of the swab body mandrel 1; and that the washing tool can be converted into a swab by merely exchanging the mandrel 1A for the 55 mandrel 1.

The washing tool as illustrated in Fig. 7, without any change, except the addition of perforated nipple 5, Fig. 1, can be used for a swab, as was described for the swab illustrated in Fig. 1. If 60 so employed only the lower rubber, however, will be completely expanded by the fluid being raised. It is apparent that the pressure which expands the lower rubber will tend to be equalized on both sides of the upper rubber through openings 5a and 1Ab. The washing tool in Fig. 7, therefore, will act as a one rubber swab; while the swab in Fig. 1 employs both rubbers in the swabbing operation.

70 In this connection, however, it is apparent that the washing tool illustrated in Fig. 7 can be completely converted into a swab like the one shown in Fig. 1 by employing the clamps 13, gasket 15, and bolt 14, as illustrated in Fig. 4, to close the 75 openings 1Ab, the hole 1Ad and its opposite com-

panion hole (not shown) being provided to receive the bolt 14 for this purpose.

If it is desired to clean out behind the perforations of the casing or liner without employing the washing tool with only water or any other liquid, the same tool may be operated with compressed air or gas, pure or in combination with abrasives and/or liquids or combinations of either in the same manner as was described for employing the washing tool with fluid supplied by a 10 pump, except that the spring 8 is left out or necessarily made more sensitive for use with air or gas or air or gas in combination with abrasives or a liquid than for use with a liquid only. If the tool is to be operated with air or gas or any combination of air or gas with other solids or liquids, the nipple 6 and all contained and attached parts may be left off and replaced by a cap screwed upon the lower end of mandrel 1A, unless the well condition is such that the tool or pipe upon which 15 it is run might become struck by the dislodged matter lodging between the pipe 16 and the casing. In the event of any such danger a light spring should be employed which will enable the pipe 16 to be pumped through if necessary. If 20 the tool is used with air or gas only the pipe 16 may be connected to a compressor. If it be desired that abrasives or liquids be mixed with the air or gas to accomplish better cleaning out results, a pump and/or means for inserting abrasives may be also connected into the pipe 16, such pump connection and/or intake for abrasives being preferably made below the compressor connection.

If both liquid and abrasives are employed in 35 combination with compressed air or gas, the abrasives preferably should be fed into the pipe 16 below the connection through which the liquid is admitted.

It is apparent that many minor changes in 40 construction can be made within the scope of the stated objects and appended claims, which changes I reserve the right to make.

I claim:

1. A swab including a mandrel, a pair of spaced 45 sets of perforations therein, spaced cup members fixed to the periphery of said mandrel above and below each set of openings, an expandable rubber packing sleeve retained by said cups and overlying said openings, reinforcing protective wires 50 along the outside of said packings, and a shield member in each cup to receive and retain the ends of said wires.

2. A packing assembly for swabs and washing tools including a support, a pair of spaced cups thereon, a grooved shield at the inner end of each cup, a plurality of protective wire members having the ends thereof seated for sliding in said shields, and a resilient packing disposed in said cups and protected by said wire members and shields, each shield comprising a corrugated frusto-conical ring to receive the ends of the 55 wires in the corrugations.

3. A combination swab and washing tool including a mandrel, a pair of spaced sealing packings thereon, a closure means for the lower end of said mandrel, openings through said mandrel so that pressure therein may expand said packings, and discharge ports through said mandrel between said packings so that both packings may 60 form a seal when the mandrel is held stationary and fluid under pressure discharged thereinto, or said lower packing may form a seal when the tool is moved upwardly, and means to reinforce 65 said packings including wires shaped to lie along 70 75

the outside of the packing, and a shield member adjacent each end of the packing to receive and retain the ends of said wires.

4. In a swab, the combination of a mandrel, a pair of cylindrical expandible members having tapered ends and peripheral longitudinal grooves intermediate said ends, a pair of proximately positioned fixed annular cups upon said mandrel, said cups containing the proximate tapered ends 10 of said expandible members, a second pair of annular cups upon said mandrel, said second cups containing the opposite tapered ends of said members and being longitudinally adjustable upon said mandrel, locking means on said mandrel to secure said second cups in relation to said expandible members, lateral openings in said mandrel opposite said expandible members, a shield within each of said cups, said shields having longitudinal channels adapted to register with 15 said grooves, spaced protector wires in said longitudinal grooves and channels, the ends of said wires being slidible between said cups and said shields, and a check valve in the lower end of said mandrel, said valve being adapted to be opened by pressure from below said mandrel and to be closed by pressure within the same.

5. In a swab, the combination of a mandrel, a pair of cylindrical expandible members and a pair of proximately positioned cups upon said mandrel, said cups containing the proximate ends of said expandible members, a second pair of cups upon said mandrel, said second cups containing the opposite ends of said members, lateral openings in said mandrel opposite said expandible 30 members, a shield within each of said cups, spaced protector wires longitudinally of said expandible members, the ends of said wires being slidible between said cups and said shields, and a valve closure means in the lower end of said mandrel.

6. A swab comprising a mandrel, a pair of cylindrical expandible members and a pair of proximately positioned cups upon said mandrel, said cups containing the proximate ends of said expandible members, a second pair of cups upon said mandrel, said second cups containing the opposite ends of said members, lateral openings in said mandrel opposite said expandible members, spaced protector wires longitudinally of said expandible members and embedded therein, said wires having the ends thereof slidible within said cups, and a check valve in the lower end of said mandrel, said valve being adapted to be opened by pressure from below said mandrel and to be closed by pressure within the same.

7. A washing tool comprising a mandrel having its upper end adapted to be joined to a string of pipe, a pair of cylindrical expandible members upon said mandrel, said members having each end tapered and having longitudinal peripheral grooves exterior thereof between said ends, a pair of proximately positioned fixed annular cups upon said mandrel, said cups containing the proximate tapered ends of said expandible members and having longitudinal internal channels adapted to register with said grooves, a second pair of cups on said mandrel, said second cups containing the opposite tapered ends of said expandible members and being longitudinally adjustable relative to said members, said second cups also having longitudinal internal channels adapted to register with said grooves, spaced protector wires in said grooves and channels, the ends of said wires being slidible in said channels, lateral openings in said mandrel opposite said

members, second lateral openings in said mandrel between said proximate cups, and a check valve in the lower end of said mandrel, said valve being adapted to be opened by pressure from below said mandrel to be closed by pressure within the same. 5

8. A washing tool comprising a mandrel having its upper end adapted to be joined to a string of pipe, a pair of cylindrical expandible members around said mandrel, said members having each end tapered and having external longitudinal grooves intermediate said ends, a pair of proximately positioned fixed annular cups upon said mandrel, said cups containing the proximate tapered ends of said expandible members, a second pair of cups on said mandrel, said second cups containing the opposite tapered ends of said expandible members and being longitudinally adjustable relative to said members, a metallic shield within each of said cups, said shields having longitudinal channels adapted to register with said grooves, spaced protector wires in said grooves and extending into said channels, lateral openings in said mandrel opposite said members, second lateral openings in said mandrel between said proximate cups, and a spring loaded check valve in the lower end of said mandrel, said valve being adapted to be opened by pressure from below said mandrel and to be closed by pressure within the same.

9. A combination swab and washing tool assembly comprising a mandrel, a pair of expandible members thereon having longitudinal peripheral grooves and tapered ends, a pair of proximately positioned fixed annular cups upon said mandrel, said cups containing the proximate tapered ends of said expandible members, a second pair of cups on said mandrel, said second cups containing the opposite tapered ends of said members and being longitudinally adjustable relative thereto, an annular shield within each of said cups, said shields having longitudinal channels adapted to register with said grooves, spaced protector wires in said channels and grooves, the ends of said wires being slidible in said channels, lateral openings in said mandrel opposite said members, second lateral openings in said mandrel between said proximate cups, a check valve in the lower end of said mandrel, said valve being adapted to be opened by pressure from below said mandrel and to be closed by pressure within the same; clamp means for closing said second lateral openings in forming a swab, and means for connecting the upper end of said tool to a perforated nipple having means for attachment upon a cable to complete said swab and means for connecting a pipe to the upper end of said mandrel for converting said assembly into a washing tool. 55

10. In a tool for cleaning wells and removing liquid therefrom, an assembly comprising an annular expandible member upon a mandrel, said member having tapered ends and peripheral longitudinal grooves exterior thereof intermediate said ends, lateral openings in said mandrel opposite said member, confronting metallic cups on said mandrel housing said tapered ends, shields within the ends of said confronting cups, said shields having longitudinal channels adapted to register with said grooves, and protector wires in said grooves and channels. 60

11. In a tool for cleaning wells and removing liquid therefrom, an assembly comprising an annular expandible member upon a mandrel, said member having tapered ends and peripheral longitudinal grooves exterior thereof intermediate 70

- ate said ends and said mandrel having lateral openings opposite said member and confronting metallic cups housing said tapered ends, one of said cups being adjustable relative to said member, means upon said mandrel for securing said 5 adjustable cup, a shield within the end of each of said cups, said shields having longitudinal channels adapted to register with said grooves, and protector wires in said grooves and channels.
12. In a tool for cleaning wells and removing liquid therefrom, a mandrel, an assembly comprising an annular expansible member upon said
- mandrel, said member having tapered ends and exterior longitudinal grooves exterior thereof intermediate said ends, lateral openings in said mandrel opposite said member, cups on said mandrel housing said tapered ends, one of said 10 cups being fixed upon said mandrel and the other being adjustable thereon relative to said member, longitudinal channels in said cups, said channels being adapted to register with said grooves, and protector wires in said grooves and channels. 10

ALEXANDER BOYNTON.
